DESIGN FOR A TEXTILE FABRIC OR SIMILAR ARTICLE

Milton M. Cann, Brooklyn, N. Y.

Application March 12, 1942, Serial No. 106,168

Term of patent 3½ years

To all whom it may concern:

Be it known that I, Milton M. Cann, a citizen of the United States, residing in Brooklyn, N. Y., county of Kings and State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article showing my new design.

The figure shows the entire width of the fabric from selvage to selvage.

I claim:

The ornamental design for a textile fabric or similar article as shown and described.

MILTON M. CANN.
